(57) **CLAIM**

The ornamental design for a watch, as shown and described.

DESCRIPTION

FIG. 1 is a front elevational view of the present invention;
FIG. 2 is a right side elevational view of the present invention
shown in FIG. 1;

FIG. 3 is a left side elevational view of the present invention
shown in FIG. 1;

FIG. 4 is a top plan view of the present invention shown in
FIG. 1;

FIG. 5 is a bottom plan view of the present invention shown in
FIG. 1;

FIG. 6 is a rear elevational view of the present invention
shown in FIG. 1; and,

FIG. 7 is a perspective view of the present invention shown in
FIG. 1.

The broken lines in the drawings are for illustrative purposes
only and form no part of the claimed design.
